UNITED STATES PATENT OFFICE.

MORTIMER NORDEN, OF NEW YORK, N. Y., ASSIGNOR TO THE ELECTRIC CARRIAGE CALL COMPANY, OF NEW YORK, N. Y., A CORPORATION OF NEW YORK.

ELECTRIC-LIGHT SIGN.

No. 881,943.

Specification of Letters Patent. Patented March 17, 1908.

Application filed August 21, 1906. Serial No. 331,445.

To all whom it may concern:

Be it known that I, MORTIMER NORDEN, a citizen of the United States, residing at the borough of Manhattan, in the city, county, 5 and State of New York, have invented an Improvement in Electric-Light Signs, of which the following is a specification.

My invention relates to that class of signs in which incandescent electric lamps are 10 illuminated in groups for the purpose of indicating letters, numerals, or characters, and it particularly relates to plates which are designed to delineate the desired characters or letters, and which plates are interchangeable 15 without disturbing the wiring.

In carrying out my invention I make use of a shallow box for each character or letter of the sign, within which box are lamp sockets so arranged as to be adapted to form a letter 20 of the alphabet, numeral or character, and I provide interchangeable plates having openings therein adapted to fit the lamps and so arranged as to exactly register with the sockets required to form the desired letter, numeral 25 or character with an outline of walls forming the contour of the letter, numeral or character attached to and projecting forward from the plates.

The boxes and the arrangement of the 30 sockets therein may be such as shown in patent to G. W. Enright, Oct. 27th, 1903, No. 742407.

In the accompanying drawing, Figure 1 is a face view of a portion of a completed sign. 35 Fig. 2 is a face view of one of the interchangeable plates. Fig. 3 is a sectional view taken transversely through the letter plate. Fig. 4 is a front view of a single character or letter box with the character or letter plate 40 removed. Fig. 5 is a vertical cross section of the same, with a portion of one of the interchangeable plates in place, and Fig. 6 illustrates a character or letter plate in which the projecting outline shell has straight walls.

The boxes *a* have bases *b*, upon which are 45 arranged parallel rows of lamp sockets *c*, permanently wired to conductors *c'* passing out through the base *b*. The arrangement of the sockets is such as to produce any one 50 of the letters of the alphabet, a numeral or character, and I prefer the arrangement shown in Fig. 4, which is like that shown in the Enright patent before referred to, although I do not limit myself to this particu- 55 lar arrangement of the lamp sockets.

Slideways *d* are formed in the walls of the box *a* near the front and parallel to the back or base *b*. I make use of flat interchangeable plates *e*, having openings *l* in them adapted to fit the lamps *g* and so arranged 60 as to exactly register with the sockets required to form the desired letter, numeral or character, with marginal walls *f* formed from strips of sheet material bent or cut to shape and surrounding the openings and attached 65 to and projecting forward from the upper surface of the plates at substantially right angles thereto, said walls forming the contour of the letter, numeral or other character. These interchangeable plates *e* embody the 70 main features of novelty in this invention and slide into the slideways *d*, the openings in the plates being arranged to exactly register with the sockets required to form the desired letter or character. After a letter 75 plate *e* has been slid into place in the box *a*, lamps *g* are inserted through the openings *l* in the plate and screwed into the sockets, registering therewith, so that the surface presented, shows only the letter or character 80 desired.

The interchangeable plates *e* are preferably made of sheet metal, but may be made of any suitable sheet material. At the back of the walls *f* of the letter outline, I provide 85 flanges *f'* by which the walls *f* are attached to the plates *e*, preferably by solder or rivets.

It is desirable to stiffen the front of the letter outline walls by bending over the outer edges thereof as shown. It is preferable to 90 make the walls *f* of the projecting letter or character outline flaring, as shown in Figs. 1, 2 and 3, so that the letters may have a greater apparent width, but they may be made parallel throughout, as shown in Fig. 6. 95

The advantages of the present invention are that the plates *e* may be changed at pleasure while the wiring and terminal points remain permanently fixed, and the visible surface of the letter, numeral or character 100 is very clearly delineated.

I claim as my invention:

1. In an electric sign, the combination of a plurality of interchangeable plates, each having openings in the form of a letter, numeral or character, and projecting walls around said openings forming the outline of the letter, numeral or character, substantially as set forth. 105

2. In an electric sign having socket ter- 110

minals, the combination of interchangeable plates having openings in the form of a letter of the alphabet and a wall surrounding said openings and forming the contour of the letter, attached to and projecting forward from the plate, and lamps attachable to said socket terminals through the openings in said plate.

3. In an electric sign, the combination of 10 lamp sockets adapted to be arranged to form a letter, numeral or other character, a plurality of substitutable plates locatable before said lamp sockets and each having openings in the form of a letter, numeral or character,

and projecting walls around said openings 15 forming the contour of the letter, the openings in said plates being in registry with the lamp sockets arranged to form a certain letter, numeral or character, and lamps attachable to said sockets through said openings in the plate.

Signed by me this second day of April 1906.

MORTIMER NORDEN.
